UNITED STATES PATENT OFFICE.

ROBERT D. BARR, OF PITTSBURG, PA., ASSIGNOR OF TWO-THIRDS TO
WILLIAM STARKEY AND THOMAS W. DAVIS, OF SAME PLACE.

HIGH-STEAM AND LOW-WATER DETECTOR.

SPECIFICATION forming part of Letters Patent No. 268,353, dated November 28, 1882.

Application filed April 10, 1882. (No model.)

To all whom it may concern:

Be it known that I, ROBERT D. BARR, of Pittsburgh, in the county of Allegheny and State of Pennsylvania, have invented a new and useful Improvement in High-Steam and Low-Water Detector; and I do hereby declare the following to be a full, clear, and exact description thereof, reference being had to the accompanying drawings, forming part of this specification, in which—

Figure 1 is a side elevation thereof. Fig. 2 is a top view, partly in section, through line $x-x$ of Fig. 1. Fig. 3 is a vertical section through the valve-chamber. Fig. 4 is a side elevation of a modification of my device. Fig. 5 is a horizontal section through $x-x$ of Fig. 4.

In the several figures like letters of reference indicate the same parts.

My invention relates to self-acting detectors, to sound an alarm whenever the water in the boiler gets too low, and also whenever the pressure of steam in the boiler rises above that for which the apparatus is set, which are operated through the instrumentality of the expansion of a metallic tube into which live steam is permitted to enter whenever the water in the boiler falls below a given level. In order to secure the requisite degree of motion of the alarm apparatus by the direct action of the elongation of such a tube from the difference between the heat of the water in the boiler and the live steam, an expansion-tube of considerable length would ordinarily be required. In order to avoid this necessity and to permit of the use of a short expansion-tube, and thereby secure greater compactness of construction and efficiency of operation in the apparatus, and lessen its liability to accidental injury or derangement, I actuate the valve-stem of the steam-whistle by means of a lever having its fulcrum at the extremity of its short arm, and the power applied between the fulcrum and the valve to be operated interposed between the expansion-ribs and the valve of the steam-whistle, so that the short arm of such lever is operated by the former, while the long arm actuates the latter, whereby a comparatively slight elongation of the expansion-tube will effect a considerable motion of the valve-stem. The arrangement of the lever

D so that its point of connection with the expansion-tube shall be intermediate between its fulcrum and the valve-stem is designed to obviate a serious difficulty which I have found to exist in the use of a lever of the first order, 55 by causing the strain on the expansion-tube to be exerted in a plane coincident, or very nearly so, with the axis of the expansion-tube, and thereby preventing the expansion-tube being bent or drawn downward, which would 60 materially detract from the efficiency of the apparatus, the extremity of the long arm of the lever operating to raise the valve on the elongation of the expansion-tube, but not being attached to the valve, which is thus left 65 free to rise against the pressure of a weight or spring, so as to sound the whistle whenever the pressure of steam in the boiler becomes excessive. This effect is also increased by constructing the connection between the free 70 end of the expansion-tube and the lever of a metal having less expansibility than that of which the pipe is made.

In the drawings, A is an expansion-tube, made of brass or other metal having a higher 75 rate of expansion than iron.

B is a short connecting-pipe, to which the tubular downward extension E' of the valve-chamber E is firmly secured by bolts or screws a in the manner shown in Fig. 5. The expansion-tube A is screwed into the tubular piece E', thus connecting directly with the pipe B. The pipe B may be of iron, and is screwed into one of the gage-cock openings in the head of the boiler by means of a right-and-left screw-coupling, b, so that the whole detector apparatus may be removed and replaced without turning it on its axis. The connecting-pipe B may be so constructed, as shown in Fig. 1, that the expansion-tube A shall project horizontally 80 from the head of the boiler in a line with the axis of the steam-boiler, or, as shown in Fig. 5, so that the expansion-tube A may be at right angles to the axis of the steam-boiler, as may be most convenient. In the connecting-pipe B 85 is a valve, c, Fig. 5, which, when closed, shuts off the steam or water connection between the boiler and the expansion-tube A when desired, the valve c being operated by a hand-wheel, d. As the pipe B opens into the boiler just below 90

the ordinary water-line the water from the boiler fills the expansion-tube A whenever the water in the boiler is at or above the proper water-level. Should the water in the boiler 5 become too low, the water-level falls below the top of the orifice of the pipe B and live steam from the boiler enters and fills the tube A, driving the water from tube A back into the boiler.

10 A gage-cock, C, Fig. 1, at the outer extremity of tube A, serves as and may take the place of one of the ordinary gage-cocks of the boiler, and may be used as such. The introduction of a gage-cock, C, at the outer end of the horizontal expansion tube A not only permits of the substitution of my apparatus for one of the ordinary gage-cocks, but also prevents the clogging of the expansion-tube with froth or sediment, which are removed from the interior 15 of the expansion-tube every time that the gage-cock C is opened. This is very important, because otherwise the interior of the expansion-tube would become coated with sediment, which, being a bad conductor of heat, would soon impair and ultimately destroy the efficiency of the apparatus by preventing the requisite degree of expansion of the tube A. The gage-cock C, placed at the outer extremity of the expansion-tube A, besides performing the functions just stated, affords a ready means of testing at any time whether the apparatus is in 20 good working order. When the water in the boiler is at the proper height above the top of the pipe B, and the expansion-tube is consequently filled with water, it is only necessary to open the cock C for a sufficient length of time to allow the comparatively cool water which it contained to run out through the vent-pipe f, when its place will be immediately supplied by water directly from the boiler, which, being much hotter than the water with which the expansion-tube A is ordinarily filled, will cause it to expand and elongate, raising the valve and sounding the whistle, if the apparatus 25 is in good working order, in the same way as if steam were admitted to the expansion-tube. When the cock C is turned merely to test the height of the water in the boiler it need not be left open long enough to sound the 30 whistle. As an apparatus of this description operates automatically only in case of danger from too high steam or too low water, it is liable to become clogged from disuse. Hence the importance of a ready means of testing its condition, such as is afforded by the gage-cock C.

35 When the water is at such a height in the boiler that the tube A is filled with water the pipe is exposed to a temperature of about 140° Fahrenheit; but if the water in the boiler falls so low as to admit steam into tube A, it is then exposed to a very much higher heat, so that the tube A expands longitudinally as soon as steam is thus admitted, and it is by this elongation of the expansion-tube A that the detecting apparatus operates to indicate and give 40 warning of the fact that the water is too low in the steam-boiler. In order to secure suffi-

cient elongation of the expansion-tube A to operate the apparatus it should be made of brass and be from seven to ten inches in 70 length.

A cap, e, is screwed onto the outer extremity of tube A, in which is placed the valve-seat of the gage-cock C, and from which a vent-pipe, f, allows the passage of water or steam from 75 the tube A, as the case may be, thus indicating the height of water in the boiler.

To a collar, e', on the cap e are pivoted two arms, g g, made of iron or steel, one on each side of tube A, the other extremity of these 80 arms being pivoted to a lever, D, which lever has its fulcrum at h on a forked bracket, I, which is attached to, or is cast as a part of, the valve-chamber connecting with it both above and below the expansion-tube A, as seen 85 in Fig. 1. The forward extremity of the bracket I is an annulus, through which the tube A passes, and by which it is sustained and supported. The arms g g, being of iron, do not lengthen by heat as much as the tube A, and 90 when the tube A elongates by expansion from the additional heat to which it is exposed when steam enters it the arms g g, being pivoted above the fulcrum h of the lever D, cause the rear or free end of the lever D to rise. 95 The effect of the raising of the free end of the lever D is to raise the stem of a valve in the valve-chamber E, which admits steam to pass to the steam-whistle W. This will be better understood by reference to Fig. 3, which represents a vertical section of the valve-chamber and its connections. In the valve-chamber are two steamways, s s', one above the other. A pipe, p, from this steam-boiler (see Fig. 1) conducts live steam to the lower steamway, s. A 100 valve, v, is seated in the steam-chamber in the partition separating the two steamways s s' from each other. The stem t of the valve v extends from the valve-chamber E upward and passes through a crotch, i, in the free end of 105 the lever D, (seen in Fig. 2,) so as to be raised as the long arm of the lever is raised. When the expansion-tube is cooled and contracts by 110 the reduction of heat when the water is raised in the boiler above the level of the top of the 115 tube B, the long arm of the lever D falls and the valve is closed by the lever H and weight K or spring. The valve-stem t, not being attached to the lever D, is free to rise without moving the lever D whenever the steam-pressure under the 120 valve becomes excessive, as hereinafter explained. When the valve v is raised, live steam passes from steam-pipe p through the lower steamway, s, and through the valve-seat into the upper steamway, s', and thence passes without 125 obstruction through pipe q to the steam-whistle, thus sounding the alarm and indicating the fact that the water in the boiler has gotten so low as to admit steam into tube A. On the stem t of the valve v is a nut, n, screwed onto 130 the valve-stem above the crotch of the lever D, so that by setting the nut n up or down on the valve-stem t the valve v may be set to open more or less, as may be desired. Opposite to

the point p' in the lower steamway, s , at which the steam-pipe enters the steam-chamber E , is an orifice, k , (Figs. 4 and 5,) to which is attached a pipe and cock, j , by means of which the steam-pipe p and steam-chamber E may be relieved of any water which may collect there from the condensation of steam. A bracket, G , is attached to the pipe q , (leading to the steam-whistle,) to which bracket is pivoted a lever, H , having a sliding weight, K . The lever H extends directly over the top of the stem t of the valve v , and rests upon the valve-stem near to the fulcrum of the lever, by which means the valve is prevented from being raised by steam-pressure applied to its under surface, unless that pressure exceeds that at which the lever H is adjusted to rise by means of the weight K .

When the apparatus is in operation steam is allowed to pass freely through the pipe p into the lower steamway, s , in the valve-chamber E , and in case the steam-pressure becomes excessive the valve v is raised, and steam passing, as before described, through the upper steamway, s' , to the whistle, causes the alarm to be sounded. It will be noticed that when the whistle is sounded, in consequence of excessive pressure of steam in the boiler, the valve v is raised entirely independently of the lever D . It is obvious that the weight K may be set on the lever H so as to allow the alarm-whistle to be sounded whenever the steam-pressure in the boiler exceeds the number of pounds to which the lever is weighted, as in case of a safety-valve.

As a modification of the apparatus, an adjustable spiral spring may be substituted for the lever H and weight K . This modification is shown in Fig. 4. The upper end of the valve-stem t of the valve v is enlarged in diameter, and is bored with a screw-thread for a short distance downward to receive the end of a screw-rod, t' , which forms an extension of the valve-stem t . The upper end of this extension-piece t' plays through a bracket, w , which is adjustably attached to the steam-pipe q by a collar on the bracket and a set-screw, o , as shown in Fig. 4. Around the top of the valve-stem t is a collar, r , between which and the bracket w is placed a spiral spring, x , which surrounds the extension-piece t' of the valve-stem. This spiral spring x performs the same function as the lever and weight before described, and the downward pressure of the spring on the valve may be regulated by adjusting the height of the bracket w by means of the set-screws o .

In order to communicate intelligence to any part of a building or factory where steam power is employed, or to any part of a steam-boat, whenever the water in the boiler falls below a safe water-level, I connect an electrical alarm apparatus to the devices which I have described, as shown in Fig. 1. From one side of the crotch i of the lever D a small horizontal plate, y , projects. Above the plate y is placed

a brass rod, z , having a platinum point projecting toward the plate y , so that whenever the lever D is raised electrical contact may be formed between the rod z and the plate y . The rod z is insulated from the apparatus in any convenient and usual manner. A wire from one pole of an electric battery is connected with the insulated rod z , and the wire from the other pole is connected with the apparatus, as at z' , Fig. 1. Whenever, therefore, the electrical circuit is closed by contact between the plate y and the insulated rod z , the electrical bell is rung at any point where such bell may be placed.

If it is desired to sound the electric bell whenever the whistle is blown to indicate either excessive steam-pressure or low water in the boiler, the insulated rod z may be so placed as to come in contact with the valve-stem t , whenever it is raised either by the lever D or by pressure of steam on the valve v .

I do not in this application make any claim to the operation of an electric alarm by means of an expansion-tube for calling attention to an excessive pressure of steam or to a lack of water in the boiler, as that forms the subject-matter of another application for a patent made by me; but,

Having thus described my improvement, what I claim as my invention, and desire to secure by Letters Patent, is—

1. An apparatus for indicating either high steam or low water in steam-generators, the combination of the expansion-tube A , gage-cock C , lever D , valve t , adjusting-nut n , and weighted lever H , with a steam-whistle, W , and connecting-pipe p , constructed and arranged substantially as described.

2. The arrangement of lever D parallel with the horizontal expansion-tube, having its fulcrum at a point outside the plane of the axis of the tube and pivotally connected with the tube in or near the plane of its axis and on both sides thereof, whereby the expansion-tube may support the other parts of the apparatus without liability to derangement arising from any straining of the steam-joints, substantially as and for the purpose specified.

3. The combination, with expansion-tube A , of the bracket I , adapted to support the expansion-tube, lever D , arranged parallel with the expansion-tube and fulcrumed at one extremity on the bracket at a point outside the plane of the axis of the tube, links or arms gg , pivotally connected with the lever D , and with the expansion-tube at a point in or near the plane of its axis, a valve operated by the free end of lever D , and a whistle, substantially as and for the purpose specified.

In testimony whereof I have hereunto set my hand this 5th day of April, A. D. 1882.

ROBERT D. BARR.
